UNITED STATES PATENT OFFICE.

WILLIAM H. DALTON, OF SALEM, MASSACHUSETTS.

ELECTRIC FLAT-IRON.

1,124,303.

Specification of Letters Patent.

Patented Jan. 12, 1915.

Application filed April 10, 1912. Serial No. 689,810.

To all whom it may concern:

Be it known that I, WILLIAM H. DALTON, a citizen of the United States, residing at Salem, county of Essex, State of Massachusetts, have invented an Improvement in Electric Flat-Irons, of which the following description in connection with the accompanying drawing is a specification, like characters on the drawing representing like parts.

- 10 This invention relates to electrically-heated flatirons, and has for its principal object to provide an electric flatiron of novel construction which is designed to operate with a minimum consumption of current.
- 15 I secure this object by using a reversible iron having two ironing surfaces, either one of which can be brought into operative position, and providing electrical heating means for heating both sides of the iron simultaneously, and by making the frame in which the iron is hung of sufficient weight to make up the required load for the iron. By means of this construction it is not necessary to make the iron itself of sufficient weight to 25 properly perform the ironing operation, as the necessary load for the iron is provided in the frame and the iron can, therefore, be so constructed that its ironing surfaces may be heated with great facility.
- 30 Other objects of my invention are to improve flatirons, all as will be more fully hereinafter described and then pointed out in the appended claims.

Referring to the drawings wherein I have 35 illustrated a selected embodiment of my invention which is sufficient to disclose the principle thereof, Figure 1 is a side elevation of a flatiron embodying the invention; Fig. 2 is an enlarged sectional view on the line $x-x$, Fig. 3; Fig. 3 is a sectional view on the line $y-y$, Fig. 2; Fig. 4 shows the manner of connecting the line wires of the electric circuit to the iron; Fig. 5 is an end view of the iron-lifting device; Fig. 6 is an enlarged view of the frame for the iron; Fig. 7 is an enlarged section on the line $a-a$, Fig. 1; Fig. 8 is a detail of the frame showing a supplemental handle applied thereto; Fig. 9 is a sectional view on the line $b-b$, Fig. 50 8; Fig. 10 is an enlarged view of one end of the iron showing the manner of insulating the terminals of the heating element; Fig. 11 is a detail of the handle for reversing the iron; Fig. 12 is a section on the line $c-c$, Fig. 11; Fig. 13 is a section on the line $d-d$,

Fig. 12; Fig. 14 is a sectional view showing one way of securing the two parts of the iron together; Fig. 15 is a fragmentary view showing another way of securing the two halves of the iron together; Fig. 16 is an end view of the iron showing the position of the conductor cord in different positions of the iron.

My improved iron is capable of general use whenever any heated iron is required for smoothing or ironing purposes.

In Fig. 1 I have shown a table 1 which may be used for supporting the articles to be ironed, and the particular table shown is one designed for sustaining skins or leather, although the invention is capable of being used for laundry purposes, or for any other purpose. The table is shown as supporting a slab 2 on which the skin 3 is placed. The iron comprises generally a frame 4 which sustains the iron 5. The iron is an electrically-heated iron and it is provided with an interior chamber 6 in which is received the heating element. This heating element is in the form of a ribbon 80 formed into a coil or coils and set on edge in the chamber, the ends of the coil extending out through apertures in the body of the iron and constituting terminals to which the conductor cords are secured. I propose to 85 make my iron in two halves 7 and 8, each half having an annular flange 9 at its periphery, so that when the two halves are put together with the annular flanges 9 in alignment with each other, the chamber 6 90 for the heating element is provided. The two halves of the iron may be secured together in any suitable way, as by means of rivets or screws 10, as shown in Fig. 14, or by means of an encircling band or hoop 11 95 that embraces the two flanges 9 and is secured thereto by screws 12, as shown in Fig. 15. This iron is a reversible iron and is formed with the two ironing faces 15 and 16, either one of which can be brought into operative position.

The heating element is shown at 17 and is in the form of one or more coils of a flat ribbon-like wire having the proper electrical resistance. In the embodiment shown 105 this ribbon-like wire is formed into two coils 18 and 19 arranged with the outer turn of each coil connected to that of the other coil and with the ends of the inner turns of the coils extended and projecting through aper-

- tures 20 in the iron to form the terminals 21 to which the circuit wires 22 are connected. I have herein shown the coil 18 as smaller than the coil 19 and as occupying the nose or pointed end of the iron, but this particular arrangement is not essential, and the two coils may have any size or shape that is best suited to the shape of the iron.
- In assembling the parts of the iron a sheet 23 of mica or other insulating material is first placed in the bottom of one-half 8 of the iron and then the two coils 18, 19 are laid in position on the mica with the turns of the coils on edge, as shown, and then a suitable cement 24 having insulating properties is poured into the section 8 so as to fill the spaces between the turns of the coil and between the coil and the flange 9 thereby insulating the coils from each other, and the coils from the body of the iron. A second sheet of mica or other insulating material 25 is then placed over the coils and the ends of the inner turns of the coil are passed through apertures in this sheet and are extended through the openings 20. A layer 26 of mica or other insulating material is then placed in the part 7 of the iron and the two parts are fastened together. The interior of the iron is then completely filled with cement by introducing cement through the openings 27, 28 at the ends of the iron for the pivotal pins to be hereinafter described, the cement which is thus introduced filling in the space between the sheets 25 and 26 of insulating material and completing the insulation. When the cement is set the coils will be firmly held in place and the turns of the coils will be thoroughly insulated from each other.
- The frame 4 of the iron is formed from a single integral casting and is provided with the upper part 280 having at the ends thereof handle portions 29, 30 and also provided with depending arms 31, 32, said arms being formed as continuations of the handle portions. The iron is hung on trunnions or pivotal pins 33 which are secured in apertures 34 formed in the lower ends of the arms 31 and 32, respectively, said trunnions entering the apertures 27, 28 formed in the ends of the iron. This manner of supporting the iron permits it to be freely turned about the trunnions so as to bring either side thereof into operative position.
- The handle portions 29, 30 are wound with a strip of leather or other non-heat-conducting material to provide a hand-hold of insulating material. The handle portion 30 is made hollow to provide a passageway 300 for the reception of the conductor cord 36 that contains the wires 22 that connect to the terminals 21. The portion 280 of the frame 4 is provided with a boss 38 into which is screwed an upright tube 37 which incloses a portion of the conductor cord 36.

The frame 4 is provided with an opening 39 at the lower end of the boss through which the conductor cord emerges and said cord then passes through the hollow handle 30 and from the outer end of the latter leads 70 to the terminals 21, as clearly seen in Fig. 1.

In my device the electrical connection with the iron is such that the reversing of the iron does not bring any strain to bear on the connection between the wires 22 and 75 terminals 21. As herein shown the frame has journaled therein a shaft 40 provided with a handle 41 by which it may be turned. This shaft has rigid therewith a C-shaped arm 42 to which is pivoted one end of an 80 elastic link 43, the other end of said link being pivoted at 44 to the end of the iron 5 at a point at one side of the axis thereof, as clearly seen in Fig. 7. The position of the iron is reversed by swinging the lever 40 in 85 the direction of the arrow α , Fig. 7, with sufficient force to carry the iron up beyond the vertical position, and then swinging the lever 41 back again into the position shown in Fig. 1, this operation carrying the link 90 43 into the dotted line position Fig. 7, and reversing the position of the iron. The lever 41 is held in the position shown in Fig. 7 by means of a pin 45 thereon engaging an aperture 46 in a locking plate 47, it being understood that the lever is sufficiently flexible to permit it to be moved laterally to disengage the pin from the aperture.

During the reversing of the iron the terminals 21 and the cords connected thereto 100 swing from the position shown in Fig. 16 downwardly below the center and to the other side, and during this movement there is nothing to interfere with the cords or put any strain on the terminals.

At the top of the tube 37 I have provided a socket member 48 of insulating material which is provided with two socket terminals 49 to which the wires 22 of the conductor cord 36 are electrically connected.

51 is an attachment plug having terminals 52 adapted to enter the sockets 49 and electrically connected to the line wires 53. These wires are shown as carried in a cord 54 which may lead to any suitable source of 115 electrical supply. The advantage of this construction is that the portion of the conductor cord 36 occupying the tube 37 cannot become twisted while the iron is being used, and if in use the iron is turned about more 120 or less any twist will be put into the conductor cord 54 which is exposed and readily visible.

The handle 41 is shown as made from a strip of sheet metal which is bent at its 125 lower end into U-shape, as shown at 55, Fig. 12. 56 designates a block which is set into the space between the arms of the U-shape and which is provided with an aperture through which the reduced end 57 of 130

the shaft 40 extends, it being noted that said reduced end of the shaft also extends through apertures in the arms of the U-shaped portion 55 of the arm 41. A nut 58 on the end of the shaft clamps the parts rigidly in position. The block 56 is shown as having fingers 59 which embrace the U-portion 55 of the arm 41, said fingers serving to prevent the block from turning.

10 60 designates a supplemental horizontally-arranged handle which can be applied to the frame whenever a handle of this shape is desired. This handle is formed with a stem 61 which is adapted to be clamped to 15 the arm 31 of the frame by means of a clamping block 62.

In order to reverse the iron, it is necessary to have it suspended above the table 1 and to assist in holding it while reversing, I 20 have provided the lifting frame shown in Figs. 1 and 5. This frame comprises two uprights 63 connected together by a cross bar 64 journaled in suitable brackets 65 that are secured to the top of the table. Each 25 upright 63 has an arm 66 extending therefrom to which is connected one end of a contracting spiral spring 67, the other end of said spring being secured to the table. The springs 67 tend to hold the frame in 30 the full line position Fig. 1. The tube 37 is provided with an arm or rest 68 which can be adjusted vertically thereon. When it is desired to reverse the iron the frame 63 is swung into the dotted line position Fig. 1 35 and the iron is moved toward the frame until the arm 68 passes above the cross bar 64. When the parts are in this position the swinging of the frame into the full line position will lift the iron off the table and bring 40 it into a position where it can be reversed without contacting with the table. The springs 67 are under the greatest tension when the parts are in the dotted line position shown in Fig. 1, and, therefore, these 45 springs assist materially in lifting the iron as the frame is swung into the full line position.

I have shown in Fig. 10 a manner of insulating the terminals from the flange 9 of 50 the two iron sections. As shown, said terminals are inclosed in a sleeve 71 of insulating material which fits into the aperture 20. This sleeve can conveniently be made by two right angular pieces of insulating material that are inserted into the aperture. After the sleeves are in place and the cement 24 is poured in, said sleeves become firmly locked in position by the cement, and said sleeves together with the 55 cement completely insulate the terminals from the iron.

In manufacturing my iron, I propose to make the iron 5 only of sufficient size to contain the heating element and to provide 60 the ironing surfaces of the requisite extent,

and I propose to secure the necessary load for the iron by making the frame 4 of more or less weight. The advantage of this is that I can maintain the ironing surfaces of the iron at the required temperature with a 70 less consumption of current than where the iron itself is made heavy enough to provide the necessary load or weight. With my construction the heat is conveyed from the heating element to the ironing surfaces by 75 conduction and both surfaces will be heated simultaneously. Because of the fact that the iron 5 itself does not contain a superfluous amount of metal the ironing surfaces can be rapidly heated. When the iron is 80 being used the ironing surface which is in contact with the material being ironed will, of course, be losing its heat, although heat will be continually supplied thereto from the heating element. When the ironing surface in use has cooled below the efficient point, then the iron can be reversed, thus 85 bringing into operative position the other ironing surface which has been accumulating heat. While the ironing is done with 90 this latter ironing surface, the first surface is being heated again and because of the construction of my iron, these surfaces not in use can be rapidly heated. I find that with this arrangement the ironing surfaces can 95 be kept at the efficient temperature with a much less consumption of current than would be possible if the iron 5 had sufficient metal in it to constitute the necessary load or weight for the ironing operation.

100 Another advantage of my improved construction is that since the ironing surfaces are polished, they do not readily radiate heat, and, therefore, there will be a minimum loss of heat due to radiation from the 105 ironing surface not in use. Moreover, since the metal necessary to constitute the weight or load for the iron is in the frame 4 which does not become heated, there will be no loss of current due to heating metal which is not 110 used in the ironing operation.

Having fully described my invention, what I claim as new and desire to secure by Letters Patent is:—

1. In an electrically-heated flatiron, the 115 combination with a body having a chamber, of a resistance element in said chamber in the form of a flat ribbon of resistance material made into two coils which are coiled in opposite directions with the outer turn of each 120 coil connected to that of the other coil and the ends of the inner turns of each coil being carried across the coils and through the edge of the iron, and wire terminals on the exterior of the iron to which said ends are 125 connected.

2. The method of making a flatiron comprising a chambered body made in two parts, each having a portion of the chamber therein, and a resistance material within 130

- said chamber, which method consists in placing a coil of resistance material in one part of the body, filling the chamber in said part of the body with cement having insulating properties, which cement insulates the turns of the coils from each other, placing the two parts of the body together, and filling the remaining portion of said chamber with cement.
- 10 3. In an electrically-heated flatiron, the combination with a frame having a hollow handle, of an electrically-heated iron pivotally sustained by said frame and provided with terminals which move with the iron as it turns about its pivot, and a conductor cord extending through the hollow handle and leading from said handle to the terminals, the length of the cord between said handle and the terminals being sufficient 15 to permit the iron to turn on its pivot without placing any strain on the cord.
4. In an electrically-heated flatiron, the combination with a frame formed as an integral structure and comprising a top portion, two handle portions, one at each end thereof, and a depending arm extending downwardly from each handle portion, of an electrically-heated iron pivotally sustained by said arms and provided with terminals, one handle portion being hollow to 20 form a cord-receiving passage, and a conductor cord extending through said passage and connected to the terminals.
5. In a flatiron, the combination with a frame, of an electrically-heated iron pivotally sustained thereby and provided with terminals, a tube secured to and rising from the frame and provided at its upper end with a socket member having two terminal- 25 receiving recesses, a conductor cord extending through the tube and having wires connecting said recesses with the terminals of the iron, and an attachment block separable from the socket member and having terminals to enter said recesses.
6. In a flatiron, the combination with a frame, of an iron pivotally sustained thereby, a shaft journaled in the frame, connections between the shaft and iron whereby 30 turning movement of the shaft reverses the iron, a handle for turning the shaft provided with a U-shaped end through both arms of which said shaft extends, and a spacing block between said arms and enclosing the shaft, said block having fingers 35
- to embrace the U-shaped portion of the handle.
7. In an iron, the combination with a revolvable ironing member having a plurality of separate smoothing faces, of means for electrically heating simultaneously all the ironing faces of said member, and a frame in which said member is revolvably sustained, said frame having sufficient weight to provide the necessary load for the iron. 60
8. In an iron, the combination with an ironing member having two separate independent ironing faces but having insufficient weight of itself to provide proper loads for the ironing operation, of electrical means for heating the ironing member, and a frame in which said member is reversibly sustained and which has sufficient weight to provide the necessary load for the iron. 70
9. The combination with a table, of an iron having a stem extending therefrom, an arm extending laterally from the stem, an iron-lifting device pivoted to the top of the table and provided with a cross bar to 75 engage the finger on the stem of the iron, and a spring acting on the lifting device and tending to throw it into operative position.
10. The combination with a table, of an iron provided with a stem having a laterally-extending finger, an iron-lifting device comprising two arms pivoted to the top of the table and connected by a cross-bar, each arm having a laterally-extending portion, and a spring connected to each laterally-extending portion whereby when the arms are swung against the action of the spring the cross-bar is brought into position to engage the finger associated with the iron. 80
11. In an iron, the combination with a reversible ironing member having a plurality of separate smoothing faces, a frame in which said member is revolvably sustained, said frame having sufficient weight to provide the necessary weight for the iron, and means to lock the iron with any one of its smoothing faces in operative position. 90
- In testimony whereof, I have signed my name to this specification, in the presence of two subscribing witnesses.
